Primary Examiner — Robert M Spear*Assistant Examiner* — Darcey E Heflin(74) Attorney, Agent, or Firm — Conley Rose, P.C.; Kristin Jordan Harkins(57) CLAIM

The ornamental design for a storage box with display, as shown and described.

DESCRIPTION

FIG. 1 is a rear perspective view of a first embodiment of a storage box with display in accordance with our new design, shown with a pair of shoes in the box;

FIG. 2 is another rear perspective view of the storage box with display, shown without a pair of shoes in the box;

FIG. 3 is a top elevation view thereof;

FIG. 4 is a bottom elevation view thereof;

FIG. 5 is a side elevation view thereof;

FIG. 6 is another side elevation view thereof;

FIG. 7 is a front elevation view thereof;

FIG. 8 is a rear elevation view thereof; and,

FIG. 9 is a front perspective view thereof depicting a display photo or card being inserted into the storage box with display.

The broken lines shown in the drawings are only provided to illustrate the environment of the design, and form no part of the claimed design.

1 Claim, 5 Drawing Sheets(56)
